[57] CLAIM

The ornamental design for a pedal for automobiles, as shown and described.

DESCRIPTION

FIG. 1 is a top, front perspective view of a pedal for automobiles showing my new design.

FIG. 2 is a top view thereof.

FIG. 3 is a front view thereof.

FIG. 4 is a right side view thereof, the left side being a mirror image.

FIG. 5 is a top, front perspective view of a second embodiment of my invention.

FIG. 6 is a top view of FIG. 5.

FIG. 7 is a front view of FIG. 5; and,

FIG. 8 is a right side view of FIG. 5, the left side being a mirror image.
